Specification for Design.

Patented July 6, 1915.

Application filed May 12, 1915. Serial No. 27,726. Term of patent 14 years.

To all whom it may concern:

Be it known that I, BERNARD P. WAGNER, a citizen of the United States, and a resident of Sidney, county of Shelby, and State of Ohio, have invented a new, original, and ornamental Design for Percolators, of which the following is a specification, reference being had to the accompanying drawing, forming part thereof.

In said annexed drawing the single figure

there appearing, is a view in perspective of the percolator.

I claim:—

The ornamental design for a percolator as shown.

Signed by me this 10 day of April, 1915.

BERNARD P. WAGNER.
